UNITED STATES PATENT OFFICE

JOHN GEORGE BRINKMAN, OF KANSAS CITY, MISSOURI, ASSIGNOR TO THE NATIONAL MARKING MACHINE COMPANY, OF CINCINNATI, OHIO, A CORPORATION OF OHIO

LAUNDRY-MARKING MACHINE

Application filed September 19, 1927. Serial No. 220,485.

My invention relates to marking machines and more particularly to devices of this character for marking laundry or the like by striking type against the articles to be marked while the latter are held against a suitable platen, the object of the invention being to provide a suitable type carrier, and means for actuating the carrier to impart a sharp, hammer-like blow of the type against the article to be marked.

In accomplishing this object I have provided improved details of structure, the preferred forms of which are illustrated in the accompanying drawings, wherein:—

Fig. 1 is a side elevation of a laundry marking machine embodying my improvements, part of which is broken away to show the type storage.

Fig. 2 is a plan view of a portion of the machine frame, showing the operating lever and a part of the type arm and its operating mechanism.

Fig. 3 is a transverse section on the line 3—3, Fig. 1.

Fig. 4 is a longitudinal section through the operating parts on the line 4—4, Fig. 3, showing also suggested means of association of the type carrier with other mechanism.

Fig. 5 is a perspective view of the operating lever and crank arm, and a rack bar reciprocated thereby.

Referring in detail to the drawings:

1 designates a casing or frame including a top plate 2 and an outer side wall 3, shown as provided with transparent panels 4. A shaft 5 is fixed in bearing blocks 6 and 7 extending upwardly from the top plate adjacent the wall 3, and a bifurcated type carriage or type arm 8 is pivotally mounted on the shaft 5. The type carriage comprises a type holding head 9 for holding the type form 9' and spaced legs 10 and 11, the ends of the legs being pivotally mounted on said shaft, each exteriorly to one of the bearing blocks. Means for actuating the type arm include preferably a pinion 12, which may be a gear segment, fixed on the end of the leg 10 of the type carriage adjacent the frame member 3; and a reciprocable arm-engaging member 13 shown as a vertical rack bar extending

through a suitable opening in the top plate with its teeth in engagement with the pinion. A roller 14, supported by a bracket 15 secured to the top plate, is positioned to be movable in a groove 16 in the back of the rack bar as 55 preferred means for holding the bar against the pinion while the bar is reciprocated, to confer motion on the type arm, by a lever 17 and connections thereof, shown in detail in Fig. 5, to be particularly described.

A lever shaft 18 is journaled in bearing openings 19 and 20 respectively in the wall 3 and a supporting plate 21 depending from the top plate, the shaft extending outside the wall 3 and the lever being fixed to the shaft exteriorly of the wall. 22 designates a crank arm keyed to the shaft 18 and pivotally connected with the lower end of the rack bar by a pin 23, the arm extending substantially parallel to the lever but being positioned on the opposite side of the wall 3 therefrom.

Vertical movement of the lever is designed to cause rotation of the arm 22 to reciprocate the rack bar, which in turn operates the pinion to swing the type carriage. The type carriage is retracted by a spring 24 having one end looped over the leg 11 and its other end fixed in the frame by the screw 25.

Suitable members are provided to support articles to receive the impression of the type, such as a boss 26 positioned on the frame in the path of the rotatable type beam carriage, having a platen 27 on which stock or an article to be stamped may be positioned, and a holding device including a frame 28 fixed to the top plate, a clip finger 29 hinged thereto and a spring member 30 impelling the finger against the frame plate.

Means for latching the reciprocating rack bar against normal downward movement and so preventing the actuation of the type beam is illustrated as a pawl 31, having a shoulder 32 and lip 33 on its upper end, which is pivotally mounted on a pin 34 supported by the frame, the pawl being impelled by a spring 35 into engagement with the rack bar, the lower end of which may seat upon said shoulder, the lip 33 restraining the pawl in engagement with the rack bar.

The pawl may be displaced by manual

means to permit the lever to actuate the rack bar and type carriage.

I illustrate a means of associating the stamping mechanism of this invention with other elements of a marking machine, including an ear 36 on the lower end of the pawl, a cam plate 37, which may be moved in connection with the operation of mechanism not shown, the cam having an outwardly projecting pin 38 which may be assumed to contact the ear of the pawl to pivotally move the pawl from latching engagement with the rack bar, the pawl being returned by the spring 35 to engagement with the rack bar upon elevation of the rack bar and suitable movement of the cam.

Said associated mechanism forms no part of the present application and invention and the means of actuating the said associated elements has no part in the actuation of my mechanism, being shown merely as possible means for preventing actuation of the stamping mechanism except at periods consonant with the operation of such associated elements.

Assuming the parts to be constructed and assembled as described, the carriage provided with type from the type storage designated 39 to provide the type form 9' for printing initials or a name on the articles to be marked, and an article to be marked applied to the platen, the pawl 31 is released from its latching engagement with the rack bar, either manually or automatically, and the lever 17 manually depressed to rotate the shaft 18 and oscillate the crank arm 22 to depress the rack bar 13. The rack bar, engaged with the pinion 12, rotates the same and therewith swings the type carriage in an arc to contact the article positioned on the platen, the lever 17 and the arm 22 providing a substantial leverage so that a relatively small force can confer a relatively large amount of pressure; and the rotation of the shaft 5 by the crank arm 22 through the rack bar conferring a rapid motion to the type beam whereby the beam is caused to deliver a swift and sharp hammer-like blow. The type beam is preferably returned to normal position by the spring 23, the pawl 31 being retracted to latching engagement with the rack bar by the spring 35.

Attention is called to the provisions of the roller 14 frictionally engaging the rack bar 55 in the groove 16, whereby the reciprocating rack bar actuated by a circularly rotating arm, namely crank arm 22, is retained in engagement with the pinion while tilting from perpendicular position. In other words, the 60 lower end of the rack bar follows the outer end of the crank arm 22 in its circular motion, the rack bar pivoting on the point between the pinion and the roller at any moment lying in a line joining the axes of the 65 pinion and the roller.

What I claim and desire to secure by Letters Patent is:

1. In a marking machine, including a frame, a platen, a pivoted type carrier, and a type form in the carrier, means for actuating the type carrier to bring the type form into contact with the platen comprising a gear on the type carrier, a rack bar meshing with the gear, an actuating shaft journaled in the frame, an arm on the actuating shaft and connected with the rack bar, and an actuating lever for the shaft. 70

2. In a marking machine, a platen, a pivoted type carrier, a type form in the carrier, means for actuating the type carrier to bring the type form into contact with the platen comprising a gear on the type carrier, a rack bar meshing with the gear, an actuating shaft, an arm fixed to the actuating shaft and pivotally connected with the rack bar, an actuating lever for the shaft, and a detent for latching the rack bar. 80

3. In a marking machine including a movable cam responsive to operation of the machine, a platen, a pivoted type carrier, a type form in the carrier, means for actuating the type carrier to bring the type form into contact with the platen comprising a gear on the type carrier, a rack bar meshing with the gear, an actuating shaft, an arm on the actuating shaft and connected with the rack bar, an actuating lever for the shaft, a detent pivoted adjacent the rack bar, means yieldingly retaining the detent in engagement with the rack bar, and means including said cam for releasing the detent to permit movement of the rack bar. 95

4. In a marking machine including operable members, a platen, a pivoted type carrier, a type form in the carrier, and means for actuating the type carrier to bring the type form into contact with the platen, a detent for latching the actuating means and means responsive to movement of said operable members for releasing the detent to permit movement of the type carrier. 105

5. In a machine of the character described including a plate adaptable for periodic movement in the operation of the machine, a platen, a type carrier, and means including a rack bar for moving the carrier, a detent for latching the bar, and means on said plate for releasing the detent to permit operation of the carrier moving means. 115

In testimony whereof I affix my signature. 120
JOHN GEORGE BRINKMAN.
